Knowles Loom Works, Worcester, Mass., a corporation of Massachusetts

Application September 24, 1945, Serial No. 618,137

10 Claims. (Cl. 139—308)

1

This invention relates to improvements in cloth roll mechanism for looms and it is the general object of the invention to provide safe and efficient means for handling large rolls of cloth.

Certain fabrics such as terry towels are quite thick and a single wrap around the cloth roll results in an appreciable increase in its diameter. Cloth rolls for looms weaving such fabrics are ordinarily mounted so that they can attain to a large diameter, thereby permitting the winding of a considerable length of fabric on the roll before taking off a cut. In the past either straight or segmental racks have been used to mesh with pinions on a shaft connected to the inner ends of large spiral springs. The other end of each spring is connected to a gear under control of a hand wheel. The hand wheel has a worm and worm gear connection with the main gear which serves to hold the gear so that as the roll descends due to its increasing diameter the shaft will turn and place the spring under increasing tension. When removing a cut from the roll of these prior looms it is customary to push the roll downwardly manually a short distance and then put some form of temporary stop between the rack and its pinion to hold the roll down in such position as will permit lifting of its gudgeons out of their pockets on the racks. After the cloth has been removed it is necessary to restore the roll to its high position and this is done by removing the temporary stop. In this last operation the workman is occasionally injured due to the fact that the spring is under considerable tension and acts to lift the roll as soon as the stop is removed.

It is an important object of our present invention to provide improved means for holding the roll in low position to permit the removal of a cut without the use of the aforesaid stop, thereby eliminating risk of injury to the workman.

The worm and worm gear connected to the hand wheel and main gear has made it possible in the past to apply too high an initial tension to the spring when the roll is in high position, with the result that as the cloth roll increases in diameter the spring closes on itself and then breaks. It is a further object of our invention to provide stop means which will limit the number of rotations the hand wheel can have. This limiting mechanism is such so that when the hand wheel is in one position the spring will always exert sufficient pressure to hold the roll in high position, but when the hand wheel is turned to its other position to lower the roll preparatory to removal the spring is placed under only a small increase in tension without reaching its limit.

2

The limiting mechanism enables us to eliminate wood shear pins heretofore used to prevent damage to the spring when the hand wheel was turned too much.

It is another object of our invention to employ a manually or foot operated clutch between the main gear and the shaft which carries the pinion for the rack, and provide means such as a spring normally tending to hold the clutch in engaging position. When the clutch parts are separated a friction disk secured to the shaft is forced against a stationary friction surface for the purpose of preventing the spring from causing too rapid a rise of the empty cloth roll.

With these and other objects in view which will appear as the description proceeds, our invention resides in the combination and arrangement of parts hereinafter described and set forth.

In the accompanying drawings, wherein a convenient embodiment of our invention is set forth,

Fig. 1 is a front elevation of the lower part of the loom having our invention applied thereto,

Fig. 2 is a side elevation of the left hand side of the forward part of the loom looking in the direction of arrow 2, Fig. 1,

Fig. 3 is an enlarged horizontal section on line 3—3, Fig. 1,

Fig. 4 is a vertical section on line 4—4, Fig. 3,

Fig. 5 is a side elevation of the stop or limiting mechanism which determines the number of rotations the hand wheel can have,

Figs. 6 and 7 are diagrammatic views showing the stop mechanism in two different positions,

Fig. 8 is a diagrammatic view indicating two different positions of the cloth roll supporting rack and the left side of the loom, and

Fig. 9 is an enlarged detail plan view of the clutch teeth looking in the direction of arrow 9, Fig. 1.

Referring particularly to Figs. 1 and 2, we have shown a loom frame 10 having a breast beam 11, a lay 12, a take-up roll 13, and cloth guiding rolls 14, 15 and 16. The cloth roll 17 is mounted in pockets 18 on two segment racks 19 and 20 having teeth 21 and pivoted at opposite sides of the loom as at 22.

The fabric F extends forwardly and over the breast beam and then around the rolls 14, 13, 15, 16 in the order named, to the cloth roll 17. The latter frictionally engages that part of the cloth on the under side of the take-up roll and is thus caused to rotate in a counter-clockwise direction as viewed in Fig. 2 to wind up the fabric. As weaving continues the diameter of the cloth on

the roll 17 increases and the segments 19 and 20 turn in a clockwise direction as viewed in Fig. 2.

Rack 19 meshes with a driven pinion 25 secured to a shaft 26 rotatable in a horizontal bearing 27 secured to the loom frame. The shaft has secured thereto the inner end of a helical spring 28 the outer end of which is secured as by a pin 29 to the main gear 30 which rotates freely on the shaft 26.

A small upper pinion 35 meshing with gear 30 is secured to a shaft 36 rotatable in a fixed bearing 37 secured to the loom frame, and a worm gear 38 secured to shaft 36 meshes with a worm 39 secured to a shaft 40 turning in a fixed bearing 41. A hand wheel 42 is secured to the front end of shaft 40 and has a ratchet 43 thereon to cooperate with a hold pawl 44 pivoted to bearing 41. The hold pawl 44 prevents clockwise rotation of the hand wheel 42 as viewed in Fig. 1, but can be lifted to permit clockwise rotation of the hand wheel.

A lower pinion 45 meshing with the main gear 30 is secured to the left end of a shaft 46 rotatable on the loom and extending across the latter and having secured to the right end thereof as viewed in Fig. 1 a second lower pinion 47 meshing with a large gear 48 at the right hand side of the loom and similar to gear 30. A second spring 49 at the right end of the loom has its ends connected respectively to the gear 48 and a second shaft 50 in a manner not shown but similar to corresponding structure at the left hand side of the loom. A pinion 51 similar to pinion 25 is secured to shaft 50 and meshes with the right segmental rack 20. The purpose of the shaft 46 and the lower pinions connected to it is to cause the segments 19 and 20 to turn in unison by reason of the trains of mechanism including the lower pinions 45 and 47 and the pinions 25 and 51.

The matter thus far described is similar to the cloth control mechanism shown in prior Patent No. 2,057,409, issued to Bergstrom and Palmer, and except as appears hereinafter operates as does the mechanism shown in that patent.

In carrying our present invention into effect we provide a friction disk 60 slidable on but keyed as at 61 to the shaft 26. This disk has a hub 62 grooved to receive the pins 63 of a clutch operating lever 64 pivoted as at 65 on the outer bearing stand 66 for shaft 26. An inwardly extending arm 67 forming part of the clutch lever has a pin and slot connection 68 with a manual or foot operated lever 69 pivoted on a fixed stud 70.

The bearing stand 66 has secured thereto a friction plate 71 for cooperation with the friction disk 60. A compression spring 72 between the disk 60 and the plate 71 tends to move the friction disk 60 to the right as viewed in Figs. 1 and 3 away from the friction plate 71. The spring normally maintains the friction disk 60 and the manual or foot operated lever 69 in the position shown in Fig. 1 so that the disk 60 and shaft 26 can turn with the lower pinion 25 as the cloth roll descends.

The hub 15 of the main gear 30 is provided with clutch teeth 76 which engage similar clutch teeth 77 on the hub 62 of the friction disk 60. The spring 72 normally holds the clutch parts in driving or engaging relationship as shown in Fig. 3. When the clutch parts are to be disengaged the lever 69 is depressed, thereby moving the teeth 77 away from the teeth 76 and moving the friction disk 60 toward the friction plate 71.

In order to limit the number of rotations which the hand wheel can have the shaft 40 has secured

thereto a collar 80 having a stop lug 81 fixed thereto, see Fig. 5. A stop ring 82 is fast with respect to the stand 41 and has a stop lug 83 which is in fixed position at all times. Between the collar 80 and the ring or collar 82 are located several rings, five being shown at 85, 86, 87, 88 and 89, respectively. Each disk is provided with a stop lug 90 which overhangs the adjacent ring to the right thereof and is in position to engage the lug of said adjacent ring.

When hand wheel 42 is turned in a clockwise direction as viewed in Fig. 1 its lug 81 will make almost a complete rotation from the position shown in Fig. 5 and will then engage the lug 90 of ring 89 and turn the latter until it engages the lug of ring 88. These rings then turn together until the lug of ring 88 engages the lug 90 of ring 87, and this operation is repeated until the lug of ring 85 engages the fixed stop lug 83. The five rings shown in Fig. 5 permit the hand wheel to turn somewhat more than five complete rotations either to the right or left as viewed in Fig. 1, but at the end of this number of rotations the hand wheel 42 is locked against further rotation. Thus it is that the hand wheel is free to turn a given number of rotations either to the right or to the left, but cannot have more than this given number of rotations. Figs. 6 and 7 show two intermediate positions which the lugs 90 of the rings can assume during rotation of the hand wheel.

In operation, it may be assumed that the cloth roll is empty and in the high position shown in dotted lines in Fig. 8 corresponding to the position shown in Fig. 2. Under these conditions the spring 28 and 49 will be under their minimum tension which will, however, be sufficient to hold the roll 17 against the cloth on the take-up roll 13 tightly enough to establish driving connection between the two rolls. The clutch teeth 76 and 77 will be in engagement with each other and the friction disk 60 will be spaced from the friction plate 71 and the foot lever 69 will be up. As weaving continues under these conditions the diameter of the cloth on roll 17 increases and there will be a corresponding angular motion of the segments 19 and 20 as the cloth roll descends. During this angular motion of the segment 19 the lower pinion 25 will turn in a counter-clockwise direction as viewed in Fig. 2 and shaft 26, friction disk 60 and clutch teeth 77 will turn in the same direction to effect a steady increase in the tension of spring 28. During this downward movement of the cloth roll the hand wheel will be stationary and the worm gear 38 and worm 39 will serve as a lock to hold the main gear 30 and the outer end of spring 28 stationary. As clutch teeth 77 turn they slip along the teeth 76 which are stationary due to the worm and its wheel or gear and move slightly to the left as viewed in Fig. 3 against the action of spring 72, causing the friction disk 60 to approach but not quite touch the friction plate 71. Eventually the teeth 77 reach the high or left-most parts of teeth 76, Fig. 3, and are then moved to the right back into close relationship with the teeth 76 by spring 72 as shown in Fig. 9. During loom operation, therefore, the clutch teeth slip with respect to each other but tend by reason of spring 72 always to move into holding relationship to prevent clockwise rotation of shaft 26 as viewed in Fig. 2.

When the diameter of the cloth or roll 17 is large enough to require the removal of a cut of cloth, the loom will be stopped and the hand wheel will be turned to cause the train of gearing between it and the clutch teeth 77 to move the

latter in a counter-clockwise direction as viewed in Fig. 2, thereby effecting a still further lowering of the cloth roll so that the latter may be lifted out of the segment pockets 18. After the cloth has been removed from the roll 17 it is placed back in the segment pockets but will still be in low position. In order to lift roll 17 to driving relationship with the take-up roll, the foot pedal 69 will be depressed the effect of which is to disengage the clutch parts and force the friction disk 68 against the friction plate 71. While the cloth roll is still in low position, the foot pedal 69 can be lifted slightly to permit the disk 69 to slip along the plate 71 under action of the springs 28 and 49. It is in this way that the cloth roll is slowly and safely raised to its high position preparatory to the resumption of weaving.

The springs 28 and 49 will still be under more tension than is desirable before weaving is resumed due to the previous turning of the hand wheel. The latter is therefore turned in the reverse direction to relieve the extra tension applied when the cloth roll was being moved away from the take-up roll by the hand wheel.

The amount of turning which the hand wheel can have because of the stop mechanism shown in Fig. 5 is such as to prevent the workman from applying too much tension to the spring when the cloth roll is in high position. Without such a stop mechanism it would be possible for the weaver to wind the springs too tightly with the result that they would close on themselves and then break before the cloth roll could reach the low position shown in dot and dash lines in Fig. 2. The foregoing description assumes that the hand wheel will be turned in one direction for the limit of its rotations permitted by the stop mechanism when the cloth roll is being removed from the segmental racks 19 and 20, and then be turned for its full motion in the reverse direction after the cloth roll has been returned to its high position. It is to be understood, however, that the full angular motion may not always be needed.

From the foregoing it will be seen that we have provided simple means by which the worm and worm gear associated with the hand wheel together with the clutch members having the teeth 76 and 77, respectively, prevent accidental movement of the racks 19 and 20 by the springs 28 and 49. The clutch parts permit relative slipping of their teeth as the cloth roll descends, but the spring 72 always acts to reestablish holding relationship between the clutch members and a slight amount of retrograde movement of the segment gears only is possible because of the clutch teeth. When the empty roll has been returned to the lowered segments the foot pedal 69 can then safely be pressed and the springs will return the cloth roll to its high position. Furthermore, because of the stop mechanism shown in Fig. 5 the amount of wind-up of the spring by the hand wheel is limited, and this wind-up together with that associated with the filling of the cloth roll with cloth can always be within the range of operation of the torsion springs. Also, it will be seen that the hand wheel provides means for turning the segments 19 and 20 in a further downward direction preparatory to removal of the cloth roll in which position the clutch teeth hold the roll, hence it is never necessary for the weaver to touch the segments or get his fingers near the point of mesh between the segments and the lower pinions meshing with them. The stop mechanism shown in Fig. 5 is a convenient means

for limiting the number of rotations of the hand wheel, but we do not wish to be limited to this particular form of stop mechanism.

Having thus described our invention it will be seen that changes and modifications may be made therein by those skilled in the art without departing from the spirit and scope of the invention and we do not wish to be limited to the details herein disclosed, but what we claim is:

- 10 1. In a loom having a cloth roll supported on gear segment means movable to locate the cloth roll in different positions, a shaft geared to the segment means, a gear rotatable on the shaft, a spring having one end operatively connected to the shaft and the other end operatively connected to the gear so that relative movement of the gear and shaft will vary the tension of the spring, a worm gear operatively connected to said gear, a worm for the worm gear, a worm shaft to which said worm is secured mounted for rotation in such position that when said worm and worm shaft are turned in a given direction said worm wheel is effective to move the gear relatively to the shaft in a direction to tension said spring, and means including a part secured to and moving with the worm shaft and a stationary part operative after a given number of rotations of said shaft in said given direction to cause engagement of said parts to prevent further rotation in said given direction of the worm to prevent excessive tensioning of the spring.
- 15 2. In a loom having a cloth roll supported on gear segment means movable to locate the cloth roll in different positions, a shaft geared to the segment means, a spring having one end operatively connected to the shaft, a control gear for the spring operatively connected to the other end of said spring and rotatable on said shaft so that relative movement of the control gear and shaft
- 20 35 will vary the tension of the spring, a worm gear operatively connected to said control gear to cause turning of the latter when the worm gear turns, a worm for said worm gear, a worm shaft to which the worm is secured, a mounting in
- 25 40 which the worm shaft turns, said worm and worm shaft when turning in a given direction causing said worm gear to turn said control gear relatively to the first named shaft in a direction to increase the tension of the spring, and stop means including a part fixed with respect to said mounting, a plurality of stop parts on and rotatable relatively to said worm shaft, and a third part secured to said worm shaft operative after a given number of rotations of said worm and worm
- 30 45 shaft in said given direction to prevent further rotation of the worm in said given direction to prevent excessive tensioning of said spring.
- 35 50 3. In a loom having a shaft connected to a cloth roll by connections operative to cause the shaft to turn in one direction when the cloth roll moves away from the loom take-up roll and operative to cause the cloth roll to move toward the take-up roll when the shaft turns in the opposite direction, a gear on the shaft, a spring operatively connecting the shaft and gear capable of assuming varying degrees of tension when the shaft turns relatively to the gear, worm and worm gear mechanism operatively connected to the gear and effective when the worm turns in a given direction to turn the gear relatively to the shaft in a direction to tension the spring, and means effective after a given number of turns of the worm in said given direction to prevent further rotation of the worm in said given direction to
- 40 45 55 60 65 70 75 prevent excessive tensioning of the spring.

4. In a loom having a cloth roll mounted on a movable support and having a shaft operatively connected to the support in such manner that the shaft is turned in one direction when the support moves the cloth roll away from the loom take-up roll and the support is caused to move the cloth roll toward the take-up roll when the shaft turns in the opposite direction, a gear rotatable on the shaft, a spring having one end thereof operatively connected to the shaft and having the other end thereof operatively connected to the gear so that relative movement of the gear and shaft will vary the tension of the spring, means normally holding the gear stationary, a clutch member fixed with respect to said gear, a second clutch member secured to the shaft, said clutch members having teeth so formed as to permit substantial movement of the shaft relatively to the gear in that direction only which corresponds to movement of the cloth roll away from the take-up roll when said gear is held stationary and the clutch members are in engagement with each other, and means normally operative to hold said clutch members in engagement with each other.

5. In a loom having a cloth roll supported on gear segment means movable to locate the cloth roll at different distances from the loom take-up roll, a shaft geared to the segment means, a gear rotatable on the shaft, a spring having one end thereof operatively connected to the shaft and having the other end thereof operatively connected to the gear so that relative movement of the gear and shaft will vary the tension of the spring, means normally holding the gear stationary, a clutch member rigid with the gear and having clutch teeth, a second clutch member rotating with the shaft and having teeth to engage the first named teeth, and means normally tending to cause said clutch members to engage each other, the teeth being so formed that the shaft can turn relatively to the gear in a direction corresponding to movement of the cloth roll away from the take-up roll but so constructed as to limit movement of the shaft relatively to the gear in a direction corresponding to movement of the cloth roll toward the take-up roll.

6. In a loom having a cloth roll supported on gear segment means movable to locate the cloth roll at different distances from the loom take-up roll, a shaft geared to the segment means, a gear rotatable on the shaft, a spring having one end thereof operatively connected to the shaft and having the other end thereof operatively connected to the gear so that relative movement of the gear and shaft will vary the tension of the spring, means normally holding the gear stationary, a clutch member on the gear having clutch teeth, a second clutch member having clutch teeth and rotatable with and slidable along the shaft, and means normally tending to hold said clutch members in engagement with each other, said teeth being so formed as to permit relative movement of said clutch members with respect to each other in one direction only corresponding to movement of the shaft when the cloth roll moves away from the take-up roll but preventing substantial movement of the shaft relatively to the gear in the opposite direction corresponding to movement of the cloth roll toward the take-up roll.

7. In a loom having a cloth roll supported on gear segment means movable to locate the cloth roll at different distances from the loom take-up roll, a shaft geared to the segment means, a

gear rotatable on the shaft, a spring having one end thereof operatively connected to the shaft and having the other end thereof operatively connected to the gear so that relative movement of the gear and shaft will vary the tension of the spring, means normally holding the gear stationary, a clutch member rigid with the gear and having clutch teeth, a second clutch member rotatable with and slidable along the shaft and having clutch teeth to engage the first named clutch teeth, resilient means tending normally to hold said clutch members in engagement with each other, said teeth being so formed as to permit relative substantial angular movement of the shaft with respect to the gear in but one direction only corresponding to the direction in which the shaft turns when the cloth roll moves away from the take-up roll, and means to separate said clutch members against the action of said resilient means to enable the spring to turn said shaft in a direction corresponding to movement of the cloth roll toward the take-up roll.

8. In a loom having a cloth roll mounted on a movable support and having a shaft operatively connected to the support in such manner that the shaft is turned in one direction when the support moves the cloth roll away from the loom take-up roll and the support is caused to move the cloth roll toward the take-up roll when the shaft turns in the opposite direction, a gear rotatable on the shaft, a spring having one end thereof operatively connected to the shaft and having the other end thereof operatively connected to the gear so that relative movement of the gear and shaft will vary the tension of the spring, clutch members one rigid with the gear and the other rotating with but slidable along the shaft, resilient means normally holding said clutch members in engagement with each other, said clutch members having clutch teeth so formed as to permit substantial relative movement of the shaft with respect to the gear in one direction only corresponding to movement of the cloth roll away from the take-up roll when said clutch members are in engagement with each other, a friction disk movable longitudinally of the shaft with said other clutch member and rotating with the latter and the shaft, and a stationary friction plate for said disk, said disk and friction plate being so related with respect to the clutch members that when the latter are disengaged said disk will engage said plate to resist movement of the shaft in a direction corresponding to movement of the cloth roll toward the take-up roll by a force derived from the spring.

9. In a loom having a shaft connected to a cloth roll by mechanism which causes the shaft to turn in one direction when the cloth roll moves away from the loom take-up roll and causes the cloth roll to move toward the take-up roll when the shaft turns in the opposite direction, a spring having one end thereof operatively connected to the shaft and tending to turn the latter in said other direction, clutch members one of which is normally stationary and the other of which rotates with and is slidable along the shaft, resilient means tending to hold said clutch members in engagement with each other, said clutch members being so constructed as to permit substantial turning of the shaft in said one direction only when the clutch members engage each other, friction means secured to said other clutch member, a stationary friction member for engagement with said friction means, said friction

means and friction member being so related with respect to said clutch members that when the latter are disengaged said friction means will engage said friction member to resist movement of the shaft by the spring in said other direction corresponding to movement of the cloth roll toward the take-up roll.

10. In a loom having a shaft connected to a cloth roll by mechanism which causes the shaft to turn in one direction when the cloth roll moves away from the loom take-up roll and causes the cloth roll to move toward the take-up roll when the shaft turns in the opposite direction, spring means operatively connected to the shaft normally tending to turn the latter in said other direction corresponding to movement of the cloth roll toward the take-up roll and resisting movement of the shaft in said one direction corresponding to movement of the cloth roll away from the take-up roll, clutch means including two normally engaging members one of which turns with and is slidable along the shaft and the other of which is normally stationary, said clutch members when engaged preventing move-

ment of the shaft in said other direction by the spring, a friction disk rigid with said one clutch member, a stationary friction plate for engagement with the friction disk, and means controlled by the operator to simultaneously disengage said clutch members and causes engagement of the friction disk with the friction plate, said means permitting control of the engagement of the friction disk with the plate to regulate movement of said cloth roll by the spring in a direction toward the take-up roll.
